UNITED STATES PATENT OFFICE.

JOHN TRIGGE, OF NEW YORK, N. Y., ASSIGNOR TO HESTER CAROLINE TRIGGE, OF SAME PLACE.

DROP-LIGHT CHANDELIER.

SPECIFICATION forming part of Letters Patent No. 252,709, dated January 24, 1882.

Application filed October 18, 1881. (No model.)

To all whom it may concern:

Be it known that I, JOHN TRIGGE, of the city, county, and State of New York, have invented a new and Improved Drop-Light Chandelier, of which the following is a full, clear, and exact description.

Drop-light chandeliers have been constructed heretofore with a central drop-light; but with this construction the central parts of the chandelier are scorched and defaced by the heat rising from this central drop-light.

The object of my invention is to avoid the above-mentioned defects of a drop-light chandelier.

Reference is to be had to the accompanying drawings, forming part of this specification, in which similar letters of reference indicate corresponding parts in all the figures.

Figure 1 is a longitudinal elevation of my improved drop-light chandelier, showing the drop-lights raised and one pair of globes in section. Fig. 2 is a plan view of the burner and globe-holder for the external globe. Fig. 3 is a plan view of the burner and globe-holder for the internal globe. Fig. 4 is a plan view of the check for regulating the position of the drop-light arms in relation to the fixed-light arms. Fig. 5 is a longitudinal elevation of the drop-light chandelier, showing the drop-lights lowered. Fig. 6 is a view of two modifications of the drop-light arrangement in longitudinal elevation, the drop-lights being shown in a raised and lowered position. Fig. 7 is an elevation in perspective of the check. Fig. 8 is a vertical central section of the central portion of the chandelier.

The chandelier A is constructed with one or more arms, A', each provided at its outer end with a globe-holder, B, and a burner, C. The globe-holders consist of a hollow block, D, to which two circularly-bent spring-wires, D', are attached, so as to form about three-quarters of a circle, these spring-wires fitting into the bottom groove, a, of a globe, E, and thus holding the globe. The burner C, which is in the middle of the globe E, is attached to a U-shaped bent tube, D'', which extends upward from the hollow block or box D, under the lower edge, and along the inner surface of the globe E, to near the top of this globe, and is then

bent downward and to the middle of the globe, at which point the burner is fastened to the tube. The chandelier is further provided with a vertical central tube, F, into which a sliding tube, G, fits, which is provided with a suitable packing to prevent the escape of gas. The tube F is provided with a clamp of well-known construction for the purpose of holding the tube G in any desired position. In place of a clamp, counter-weights such as are used in central drop-light chandeliers may be provided; or any other suitable device may be used for holding the tube G in the desired position. This sliding tube G is provided with one or more arms, G', each of which is provided at the outer end with a globe-holder, B', and a forked or double burner, C'.

The globe-holder B' is constructed in the same manner as the globe-holder B; but the burner C' is forked, so that one jet-tube, b, will be near each side of the globe E', which is of such size that it can be passed within the globe E, one side of this globe E' passing within the U-shaped bend of the tube D'', and the jets of the burner C' being at the sides of the burner C. The arms G' must be of such length that the centers of the globes E and E' will be on the same vertical line. The tube F passes through a ring, F', provided with a stud, H, which rests on the edge of a collar, J, provided with a quadrant-recess, K, which collar or sleeve J is concealed behind a circular band, L, of the chandelier, or in the knob L' or the ball L'', as it is of no importance in which part of the chandelier this device is arranged. When the drop-light—that is to say, the burners on the ends of the arms G'—is raised, the globes E' will pass into the globes E, as shown, and there will be three gas-jets at the end of each fixed arm of the chandelier, the jet of the burner C being between the jets of the burner C'. If the tube G and the drop-lights are drawn downward, the globe E' will leave the globes E, as shown in Fig. 5, and a single gas-jet only remains at the end of each arm A of the chandelier. When the tube G is lowered it can be turned a quarter of a circle (or more or less) on its longitudinal axis, this movement being regulated by the size of the recess K in the upper edge of the collar or sleeve J. If 100

the tube G is turned after being lowered, the burners C' will not be below the burners C, and thus cannot scorch or deface the ends of the arms A'. Besides, a very handsome effect 5 can be produced by changing the position of the lower arms, as a two-arm chandelier can be converted into a four-arm chandelier, &c. It is evident that the tube G must be turned back to its original position before being raised, 10 as otherwise the globes E' would not pass into the globes E.

By using a forked burner, C', in the globes E' the jets are brought nearer the sides of the globe, and are more effective than a single 15 large burner in the middle. Although I prefer to use a forked burner, C', in the globes E', I do not wish to limit myself to this arrangement, for a single burner bent to one side may be provided in the globe E', and a like burner 20 bent to the opposite side may be provided in the globe E.

In the chandelier M (shown in Fig. 6) the side tubes, N N', are hollow, and the drop-light tubes O O' slide therein, and are also provided 25 with packing and devices for holding them in any desired position. The globes E' of the drop-lights fit into the fixed globes E in the same manner as previously described. An arm, P, is attached to the lower end of the rod O, 30 and to the end of this arm P an arm, Q, is articulated, to the end of which arm Q the globe-holder B' is attached. When the drop light is raised the tube O is so turned that the arm P projects toward the vertical central line of the 35 chandelier, the arm Q projecting in the opposite direction. When the drop-light is lowered the arm P is turned to project in the direction from the vertical central line of the chandelier, and the arm Q projects in the same direction, 40 so that the globe E' will project a considerable distance farther from the chandelier than the globe E does; or a tube, R, projecting toward the vertical central line of the chandelier, may be attached to the lower end of the sliding 45 tube O'; and a tube, S, slides in the tube R, the globe E' being attached to the outer end of this tube S. When the drop-light is raised the tube S is passed into the tube R, but when the drop-light is lowered this tube S is drawn out- 50 ward.

A single drop-light chandelier or burner may be constructed in the same manner—that is, with one fixed burner and with one drop-light burner.

Having thus described my invention, I claim 55 as new and desire to secure by Letters Patent—

1. The combination, with a drop-light chandelier provided with arms carrying burners and globes at their ends, of a sliding drop-light tube provided with arms carrying burners and globes at their ends and fitting into the globes on the fixed arms, substantially as herein shown and described, and for the purpose set forth.

2. The combination, with a drop-light chandelier provided with arms carrying burners and globes at their ends, of a drop-light tube provided with arms carrying burners and globes fitting into the globes of the fixed arms, and of U-shaped bent gas-burner tubes attached to 70 the end of the fixed arms, substantially as herein shown and described, and for the purpose set forth.

3. In a drop-light chandelier, the combination, with the fixed arms and the drop-light arms, of globes on the fixed arms, of globes on the drop-light arms and fitting in the globes on the fixed arms, of U-shaped bent gas-burner tubes at the ends of the fixed arms, and of forked gas-burner tube at the ends of the drop-light arms, substantially as herein shown and described, and for the purpose set forth.

4. In a drop light chandelier, the combination, with the tube F of the sliding drop-light tube G, of the ring F', the stud H, and the 85 sleeve J, provided with a recess, K, in its upper edge, substantially as herein shown and described, and for the purpose set forth.

5. The combination, with a sliding drop-light chandelier, of a swinging arm attached to the 90 lower end of the sliding drop-light tube, and carrying a burner and globe fitting within the globe of one of the fixed burners of the chandelier, as described.

JOHN TRIGGE.
